MAGNETIC HAMMER

Richard A. Scholten, Valparaiso, Ind., assignor to The Indiana Steel Products Company, Valparaiso, Ind., a corporation of Indiana

Application March 30, 1956, Serial No. 575,155

7 Claims. (Cl. 145—30)

The present invention relates to improvements in magnetic hammer structures arranged to hold a tack, nail or the like by magnetic attraction prior to driving the nail or tack home.

While there have been numerous types of magnetic hammers proposed in the past, such prior magnetic structures frequently have the disadvantages of being cumbersome, fragile, or excessively large to be received conveniently in the head of a small hammer.

The hammer structure of the present invention provides a small, highly efficient magnetic holding means which makes it readily adaptable to small hammers such as tack hammers.

In the hammer assembly of the present invention, a strongly magnetic permanent magnet is combined with a magnetic flux concentrating means to make most efficient use of the magnetic energy. With the specific structural arrangements of the present invention, the entire magnetic assembly can be made extremely small, lightweight, and resistant to impact.

An object of the present invention is to provide an improved magnetic hammer assembly having the advantages of light weight and small size.

Another object of the invention is to provide an improved hammer assembly of the magnetic type having a highly efficient magnetic circuit.

Still another object of the invention is to provide a magnetic hammer assembly which is economical to manufacture.

These and other objects of the invention, as well as various features thereof, will be apparent to those skilled in the art from the following description of the attached sheet of drawings which illustrate several embodiments of the invention.

In the drawings:

Figure 1 is a fragmentary view in elevation, and partly in cross section, illustrating one form of the present invention;

Figure 2 is a side view in elevation of the hammer assembly shown in Figure 1;

Figure 3 is a fragmentary view in elevation, and partly in cross section, illustrating a modified form of the invention;

Figure 4 is a cross-sectional view taken substantially along the line 4—4 of Figure 3;

Figure 5 is a view taken substantially on line 5—5 of Figure 6 of a hammer head embodying a modified form of the invention;

Figure 6 is an end view of the hammer head illustrated in Figure 5;

Figure 7 is an end view of a still further modified form of the invention; and

Figure 8 is a fragmentary view in elevation, and partly in cross section, illustrating still another modified form of the invention.

As shown on the drawings:

In Figure 1, reference number 10 indicates generally a hammer head composed of a ferromagnetic material

2

such as soft iron or the like. It will be appreciated that the head 10 can be formed with any shape or size depending upon the type of nails or tacks with which the hammer is to be used. The hammer assembly includes an ordinary wooden handle 11 tightly received within an aperture 12 extending through the hammer head 10.

In the particular embodiment of the invention shown in Figure 1 the striking face of the hammer head is recessed as indicated at 13 to accommodate the magnetic components. As evident from Figures 1 and 2, the magnet may consist of a permanently magnetized annular magnet 14 received in engagement with the walls of the recess 13. For most efficient results, it is desirable to employ a magnet having strong magnetic characteristics such as a magnet of the ferrite type. One suitable example of such a magnet is barium ferrite produced by compacting and sintering together about one molecular proportion of barium oxide and about six molecular proportions of ferric oxide.

Seated at the base of the recess 13 is a spacer 16 composed of a non-magnetic material such as brass, stainless steel, or the like. An annular non-magnetic spacer 17 is disposed forwardly of the permanent magnet 14 and has a forward face 18 substantially flush with the striking face of the hammer head 10.

The non-magnetic spacers 16 and 17 serve to cushion any shock arising during the use of a hammer so as to avoid the possibility of injury to the relatively brittle permanent magnet included within the head.

As indicated in Figures 1 and 2, the annular magnet 14 is magnetized in a direction which is radial with respect to the longitudinal axis of the head 10. In the illustrated embodiment, the inner periphery of the annular magnet 14 may constitute a north pole and the outer periphery a south pole.

A low reluctance path between the opposed portions of the magnet is provided by inserting a ferromagnetic pole piece 19 into the hollow interior of the annular magnet 14. The pole piece 19 also has a forward surface 21 which is substantially coplanar with the outer face 18 of the spacer 17 and also with the forward edge 10a of the head 10.

When the striking face of the hammer contacts a magnetizable tack 22 a low reluctance path is established between the outside periphery of the annular magnet 14, through the ferromagnetic head of the tack 22, into the ferromagnetic pole piece 19, and through the opposite or inner periphery of the magnet 14.

As best indicated in Figure 1, the forward edge 10a of the hammer head 10 is suitably crimped or peened over against the non-magnetic spacer 18 to hold the assembly tightly within the recess 13. If desired, additional securing means such as rivets or the like may be employed.

The form of the invention illustrated in Figures 3 and 5 of the drawings is essentially identical to that described in connection with Figures 1 and 2 except for the fact that the magnet assembly consists of a pair of semi-circular annular segments 24 and 26. This type of assembly is somewhat easier to magnetize than the continuous ring type of magnet illustrated in Figures 1 and 2. Like the other embodiment, however, the magnets 24 and 26 are both magnetized in a direction radial with respect to the longitudinal axis of the head 10 and provide flux return paths in identically the same fashion as that previously described.

The form of the invention illustrated in Figures 5 and 6 of the drawings makes use of a pair of opposed, generally rectangular bar magnets 27 and 28 again magnetized in a direction which is radial with respect to the longitudinal axis of the head 10. The head 10 is provided with a rearwardly extending slot 29. A non-magnetic spacer 31 is disposed at the base of the slot 29, and rectangular non-

magnetic spacers 32 and 35 are disposed at the forward end of the slot 29. Between the magnets 27 and 28 there is a ferromagnetic pole piece 33 which provides a low reluctance path between the opposed magnets 27 and 28 and which extends between the non-magnetic spacers 32 and 35 to provide a substantially flush striking face 34 which is coplanar with the exposed face of the spacers and the face of the hammer head 10. As seen in Figure 5, the forward end of the head 10 may be crimped or otherwise formed about the non-magnetic spacers 32 and 35, as indicated at 10b, to hold the magnetic structure securely in place. The magnets 27 and 28 themselves are tightly held against the walls of the recess 29 by virtue of their strong magnetic attraction and opposed spacers 31, 32 and 35 provide a shock absorbing means for the magnet assembly. Since the material of the head 10 itself provides a low reluctance path for the magnetic lines of force, it is not necessary that the magnets 27 and 28 abut the non-magnetic spacers 31, 32 and 35.

In order to hold the magnetic structure securely within the slot 29, the head may be provided with a pair of opposed non-magnetic plates 36 and 37 composed of a non-magnetic metal such as brass, stainless steel, or the like. The plates 36 and 37 may be soldered or welded in place to the hammer head 10.

As a further alternative, as illustrated in Figure 7 of the drawings, the magnetic assembly can be held in place by providing a rivet having a stem 39 extending through the head 10, the magnets 27 and 28, and the pole piece 33. The ends of the rivet are upset to form heads as indicated at 42 and 43 to hold the entire magnet assembly against displacement.

In the form of the invention illustrated in Figure 8 of the drawings, the hammer head 10 is provided with a transversely extending slot 44 open laterally and forwardly and having generally converging wall portions 46 and 47. A non-magnetic spacer 48 is seated against the base of the slot 44 and a pair of opposed flat permanent magnets 49 and 51 are received by magnetic attraction against the converging walls 46 and 47. A non-magnetic forward spacer 52 having a surface 53 coplanar with the forward or striking face of the hammer head 10 is tightly received within the recess 44 by crimping or otherwise forming the forward end 54 of the head 10 over the non-magnetic spacer 52. A ferromagnetic pole member 56 conformingly bridges the space between the opposed magnets 49 and 51, and extends through the non-magnetic spacer 52 to provide a forward surface 57 which is flush with the striking face of the hammer assembly. Plates, not shown, enclose the slot 44 laterally, the same as do plates 36 and 37 (Figure 6).

From the foregoing, it will be apparent that the magnetic hammer of the present invention provides a compact but highly efficient magnetic holding assembly. The materials employed are not subject to demagnetization due to passage of time, mechanical shock, or temperature variations to nearly the same extent as the type of magnetic hammer assemblies presently being employed. Furthermore, the constructions employed for the hammer assembly makes possible the use of a magnet of short magnetic length and large area which provides efficient use of magnetic materials having a high coercive force, and permits the use of permanent magnet material which is relatively weak physically.

It will be evident that various modifications can be made to the described embodiments without departing from the scope of the present invention.

I claim as my invention:

1. A magnetic hammer comprising a head composed of ferromagnetic material, a permanent magnet contained within said head and having a direction of magnetization which is radial with respect to the longitudinal axis of said head, and a ferromagnetic pole piece disposed

between opposed portions of said magnet having the same magnetic polarity.

2. A magnetic hammer comprising a head composed of ferromagnetic material, said head having a generally cylindrical recess therein, an annular permanent magnet disposed in said recess, said magnet having a direction of magnetization which is radial with respect to the longitudinal axis of said head, and a ferromagnetic pole piece disposed within said permanent magnet.

3. A magnetic hammer comprising a head composed of ferromagnetic material and having a recess in the striking face thereof, a permanent magnet structure received in said recess, a spacer between one end of said magnet and said striking face, said spacer having a surface flush with said striking face, said magnet structure being radially magnetized, and a ferromagnetic pole piece extending between opposed portions of similar magnetic polarity in said permanent magnet structure, said pole piece also having an end surface flush with said striking face.

4. A magnetic hammer comprising a head composed of ferromagnetic material and having a recess in the striking face thereof, a first non-magnetic spacer received at the base of said recess, a second non-magnetic spacer disposed at the opposite end of said recess, a permanent magnet disposed between said spacers and including a space between opposed portions thereof, said magnet being radially magnetized, and a ferromagnetic pole piece situated in said space and providing a low reluctance path from said opposed portions.

5. A magnetic hammer comprising a head composed of ferromagnetic material and having a recess in the striking face thereof, a first non-magnetic spacer received at the base of said recess, a second non-magnetic spacer disposed at the opposite end of said recess, a permanent magnet disposed between said spacers and including a space between opposed portions thereof, said magnet being radially magnetized and a ferromagnetic pole piece situated in said space and providing a low reluctance path from said opposed portions, said second spacer and said pole piece having coplanar faces defining a striking face for said hammer.

6. A magnetic hammer comprising a head composed of ferromagnetic material, said head having a recess therein, a permanent magnet comprising barium ferrite disposed in said recess, said magnet having a direction of magnetization which is radial with respect to the longitudinal axis of said head, and a ferromagnetic pole piece disposed within said permanent magnet between surfaces of the same magnetic polarity and providing a low reluctance path for said magnet.

7. A magnetic hammer comprising a head composed of ferromagnetic material, said head having a recess therein rearwardly from the striking face thereof, a pair of flat permanent magnets both in spaced relation within said recess, said magnets being magnetized in a direction which is radial with respect to the longitudinal axis of said head, a spacer between one end of said magnet and said striking face, said spacer having a surface flush with said striking face, and a ferromagnetic pole piece disposed in the space between said magnets, said pole piece also having an end surface flush with said striking face.
